UNITED STATES PATENT OFFICE.

CHARLES CARTER TOWNES, OF PORTLAND, OREGON.

PHOTOPOINT-DEVELOPING MACHINE.

1,172,074.

Specification of Letters Patent. Patented Feb. 15, 1916.

Application filed March 31, 1915. Serial No. 18,254.

To all whom it may concern:

Be it known that I, CHARLES C. TOWNES, a citizen of the United States, and a resident of Portland, in the county of Multnomah and State of Oregon, have invented certain new and useful Improvements in Photopoint-Developing Machines, of which the following is a specification.

My invention relates to the developing, fixing, and washing of photographic positives in a purely mechanical manner and in large quantities, as for amateurs, and one of the main objects thereof is to provide an apparatus which accomplishes the above results automatically.

A further object is to provide a plurality of gripping devices for successive prints suitably spaced apart and engaging the respective prints at a desired point and releasing the same at another desired point.

Another object is to provide means for moving said prints through a fixed path of suitable length to insure the proper period of time for each of the successive operations.

A further object is to provide means for maintaining each of the solutions at a desired temperature; and further objects are to provide such apparatus which is simple in construction and use, positive in results, fool-proof, composed of few parts not likely to get out of order, comparatively inexpensive, and having a wide range for prints of different sizes, and a great and continuous output.

My invention is fully described in the following specification, of which the accompanying drawings form a part, in which like reference characters refer to like parts in each of the views, and in which:

Figure 1 is a fragmentary, vertical, longitudinal section taken through my apparatus; Fig. 2 is a plan view thereof; Fig. 3 is an enlarged, fragmentary section taken on the line 3—3 of Fig. 2; and Fig. 4 is an enlarged detail of the print gripping mechanism.

In the drawings forming a part of this application I have shown a present preferred form of embodiment of my invention, comprising a frame 7 carrying a developer tank 8, a fixing tank 9, and a washing tank 10, and a prime mover 11. The motor 11 is connected, by means of a belt 12 and a pulley 13, with a drive shaft 14 also carrying pulleys 15 and 16 and a drum 17 over

which is passed an endless blanket 18, shown fragmentarily, thereby providing a horizontal conveyer portion 19. The pulley 16 of the drive shaft 14 is connected, by means of a belt 20, with a pulley 21 on a shaft 22 adjacent the opposite end of the frame 7, said shaft 22 carrying another pulley 23 and being provided with a sprocket-wheel 24 adjacent each end for endless sprocket chains 25 guided over adjacent sprockets 26 on a shaft 27, Figs. 1 and 4, over upper sprockets 28 and 29, Fig. 1, over sprockets 30 adjacent the drive shaft 14, downwardly and upwardly around sprockets 31, 32, 33, 70 34 and 35, arranged in and over the washing tank 10, downwardly and upwardly around sprockets 36 and 37 in the vertical plane of the fixing tank 9, and downwardly and upwardly around sprockets 38 in the vertical plane of the developer tank 8 to the drive sprockets 24.

The sprockets 36 are carried by a shaft 39 journaled in dependent lugs of a casing 40 containing an electrical heating element 80 only the conductors of which are illustrated, and the sprockets 38 are similarly mounted on a shaft 41 carried at the bottom of a water tank 42 provided with an inlet pipe 43 from a suitable source of supply, and with 85 an outlet pipe 44 leading to the washing tank 10, Fig. 2. A constant supply of water at desired temperature, such as 70 degrees F., is led to and through the tank 42, and a suitable overflow pipe is provided for the 90 washing tank 10, although not shown.

The developer tank 8 is slidably adjustable, vertically, on suitable guides 45, and the fixing tank 9 is similarly adjustable on guides 46, whereby said tanks may be raised to submerge the respective portions or loops of the sprocket chains in their contained solutions, or said tanks may be lowered to a point beneath said loops.

The pulley 23 on the shaft 22 is connected, by means of a belt 47 with a pulley 48 on a shaft 49 carrying a drum 50 for an endless conveyer belt 51 also guided over a drum 52, the latter drum being arranged adjacent the shaft 27 whereby the forward end of said conveyer belt 51 is projected beneath the rearward ends of the conveyer chains 25, Figs. 1 and 4, in order to carry a print into juxtaposition with said chains.

The conveyer chains 25 are joined, at suitably spaced intervals, by cross bars 53, Figs. 1, 3 and 4, of angular cross section,

having bolts 54 movable transversely therein at the ends thereof secured to a grip bar 55, coil springs being arranged on said bolts to normally maintain the bars 53 and 55 in contact with each other, and, by reference to Figs. 3 and 4, it will be seen that the ends of the grip bar are offset so as to engage fixed cams 56, which tend to separate the bars 53 and 54 for a brief period of time; 10 these cams are arranged over the forward end of the conveyer belt 51 so that a print on said conveyer belt will be carried between the bars 53 and 55 when so separated; the upper surface of the bar 55 is in the approximate horizontal plane of the conveyer belt 51 for this reason, and the cams 56 are made of a length to maintain the grip bars apart sufficiently long to permit the conveyer belt 51 to move a print therebetween, after which 20 the springs on the bolts 54 draw the bar 55 into contact with the print and the latter moves forwardly with the chains.

Arranged above the conveyer belt 51, at each side of the machine, is a guide plate 25 57 for guiding a print on the belt 51, and said guide plates carry a pivot rod 58, Figs. 2 and 4, provided with two hooked rods 59 normally resting upon the conveyer belt 51, Fig. 1, and serving as stops for an advancing print until one of the gripping elements 30 on the chains 25 is approaching gripping position. Pivotedly mounted on one plate 57, at 60, is a lever 61, one end of which is inwardly turned beneath the hooked rods 59 and the other end of which is projected along the outer side of one of the chains 25, and this chain is provided with projecting pins 62 at spaced intervals determined by the positions of the gripping elements; each 40 of these pins is adapted to depress the forward end of the lever 61 and thus raise the hooked rods 59 and permit a print, previously stopped thereby, to proceed, said print being shown at 63, Fig. 4.

45 Each sensitized positive sheet, after exposure, is fed to the conveyer belt 51 and is carried forwardly to the stops 59 until said stops are raised to permit the positive to move forwardly between the grip bars as 50 already described; the prints are thus successively engaged and carried downwardly into the developing solution, thereoutof, into the fixing solution, thereoutof, into the washing tank where a sufficiently long 55 period of subjection to the water is permitted for thorough cleansing and thence to the conveyer blanket 18 and to a desired point, release cams 64 being provided for the gripper bars similar to those already described.

The period of subjection of the prints to the action of the developing agent, the fixing solution and the washing bath, are all arbitrary, as will be understood, and the 60 temperatures of the developing agent and

the fixing solution are also arbitrary, but it will be seen that all the operations are mechanically performed and automatic. The developing is preferably by what is known as the factorial system, and it will be noted that prints of any sizes whatever, within the limits of the machine, are positively gripped and conveyed through the various steps of the treatment.

While I have shown a present preferred general arrangement, and certain details of construction, it will be obvious that I do not limit myself thereto, but may make changes thereover, within the scope of the following claims, without departing from the spirit 70 of my invention, or sacrificing its advantages.

Having fully described my invention, what I claim as new, and desire to secure by Letters Patent, is:—

1. A photo print machine, comprising a support, a tank for a developer, a tank for a fixer, means for independently adjusting the heights thereof, a washing tank, an endless conveyer movable through said tanks, and means on said conveyer for engagement 80 with a print.

2. A photo print machine, comprising a support, a tank for a developer, a tank for a fixer, means for maintaining said developer and fixer at desired temperatures, a washing tank, and endless conveyer passed through said tanks, and means on said conveyer for engagement with a print.

3. A photo print machine, comprising a support, a tank for a developer, means for leading a heated fluid thereto independently of the developer, a tank for a fixer, a washing tank, an endless conveyer passed through said tanks, and means thereon for engagement with a print.

4. A photo print machine, comprising a support, a tank for a developer, a tank for a fixer, an electrically energized heater in said fixer tank, a washing tank, an endless conveyer passed through said tanks, and means on said conveyer for engagement with a print.

5. A photo print machine, comprising a support, a tank for a developer, a tank for a fixer, a washing tank, an endless conveyer passed through said tanks, means for leading a print to said conveyer, means for preventing such print movement, means on said conveyer for rendering said prevention 110 means inoperative, and means on said conveyer for print engagement.

6. A photo print machine, comprising a support, a tank for a developer, a tank for a fixer, a washing tank, an endless conveyer 115 passed through said tanks, means for leading a print thereto, print gripping means on said conveyer, and means for opening and closing said gripping means at predetermined moments to engage a print.

7. A photo print machine, comprising a support, a tank for a developer, a tank for a fixer, a washing tank, an endless conveyer passed through said tanks, means for leading a print thereto, print gripping means on said conveyer, means for opening and closing said gripping means at a predetermined point to engage a print, means for opening said gripping means at another

point to release said print, and means for conveying said print from said machine.

In testimony whereof I have signed my name to this specification in the presence of two subscribing witnesses.

CHARLES CARTER TOWNES.
